BERNARD LIBERMAN, OF PHILADELPHIA, PENNSYLVANIA.

CIGAR-WRAPPER MOISTENER AND CONTAINER.

1,214,194.

Specification of Letters Patent.

Patented Jan. 30, 1917.

Application filed June 6, 1914. Serial No. 843,325.

To all whom it may concern:

Be it known that I, BERNARD LIBERMAN, a citizen of the United States, residing at Philadelphia, in the county of Philadelphia, State of Pennsylvania, have invented a new and useful Cigar-Wrapper Moistener and Container, of which the following is a specification.

My invention relates to humidors for cigar rolling tables.

The object is to provide improved means for containing the wrappers in a clean and suitably moist condition and easily accessible to the operator.

Referring to the drawings, which illustrate merely by way of example, a suitable embodiment of my invention—Figure 1 is a plan view of a cigar rolling table containing my invention. Fig. 2 is a front elevation. Fig. 3 is a side elevation. Fig. 4 is a longitudinal vertical section of the humidor. Fig. 5 is a vertical cross section on line 5—5 of Fig. 4. Fig. 6 is a side elevation of the foot pedal. Fig. 7 is a plan view of same. Fig. 8 is a perspective view of a modification of pedal mounting. Figs. 9 and 10 are fragmentary sectional views of the covering cloth in two positions.

Similar numerals refer to similar parts throughout the several views.

The cigar rolling table 9 is of usual type and is provided with the brackets 10 securely fastened to the sides of the table by the bolts 11. The receptacle or box 12 is preferably of cast metal such for example as iron, and lined or coated inside and out with non-oxidizable metal, such for example as zinc. This box or receptacle 12 is adapted to rest on the supporting brackets 10 and to fit snugly between the vertical extensions thereof and the side of the table. When supported in the operative position on brackets 10 the receptacle or box 12 has a substantially horizontal top while the bottom of the same lies in a longitudinal plane inclined to the horizontal, that is to say, the bottom is lower at one end of its longitudinal extension than at the other. A drain cock 13 is provided in said bottom at said lower end, for the purpose of draining the water from the box when desired. A perforated platen 14 is provided to fit within the box, having three pairs of supporting posts or legs 15, the pair at one end being shorter and the pair at the other end longer than the inter-

mediately disposed pair, in order to accommodate the inclination of the bottom of the box, and at the same time maintain the platen 14 substantially horizontal, and sufficiently elevated to support the tobacco above 50 and out of actual contact with the water 16 lying beneath the same. This platen is also coated with a non-corroding metal, such as zinc. The box 12 is also cast or otherwise provided with lugs 17 forming hinge elements, a lug 18 for supporting the drain cock 13, and a lug 19 for supporting the catch 20 hereafter to be described.

The lid 21 is preferably made of pressed metal, having hinge elements 22 at the back, 70 and on the other three sides with the bent up and over-hanging side flanges 23 and the bent up and over-hanging front flange 24. This front flange 24 has a considerable, nearly vertical, extension, which results in 75 the main top extension of the lid 21, between the hinges and said front flange, lying in a plane inclined to the horizontal. The vertically extending side and front flanges provide a substantial overlapping between the 80 lid and the front and end walls of the box making a more efficient moisture proof closure.

The upper edge of the front wall of the box is provided with a channel 26, in which 85 is fitted the strip of rubber, or other resilient material 27, projecting above the top surface of said front edge and adapted to engage the substantially horizontal flange portion 25 of the lid, thereby forming a shock 90 absorber, and also a more effective moisture seal.

The lid 21 is also provided with the metal pieces or blocks 28 at each end thereof, 95 lying flush with the top or horizontal overhanging portions of the side flanges 23. These metal pieces 28 are of sufficient weight to stiffen the lid and also add to its gravity actuation. They also afford supporting bodies for the pin 29 hereinafter described. 100 This lid is also preferably provided with a coat of non-oxidizable or non-corroding metal.

Mounted on the round bar 30 which is connected between the lower ends of the supporting legs 31, of the table, as shown in Figs. 1, 2 and 3, is the foot pedal 32 provided with the oppositely extending ears 33 each having apertures 34 either one of which 110 is adapted to receive the rod 29, thus adapt-

ing the pedal to be reversibly mounted for the purpose hereinafter to be described.

As shown in Fig. 8, the pedal is mounted on a separate stand 45, which is not attached to the table, but is adapted to be secured to the floor by screws or other suitable means. This affords means for shifting the pedal to different positions to suit the length of the operator's leg. The end 10 of the pedal near its journal support on rod 30, is provided with the pocket-like recess 35 for receiving the heel, of the operator; the portion 36 the toe. At the other end of the pedal 32 is the side extension 37, 15 the free end of which is pivotally connected with the connecting rod 38 which is in two parts, and its length adjustable by means of the slots 39 and bolts 40, so that the device may be adapted to different heights of 20 table, or on the pedal mounting shown in Fig. 8, so that the pedal may be shifted to different positions. The upper end of connecting rod 38 is pivotally connected at 49 with the horizontal lever 41, which is pivotally supported at 50 on the hanger 42 which is bolted to the table. The other end 25 of lever 41 is connected by pivot 51 with the connecting rod 43, which in turn is connected by pivot 52 with the connecting rod 44, which is connected to the pivot or pin 29 secured to the lid 21. Connecting rod 43 is provided with the notch 46 and rod 44 is provided with the notch 47.

Where it is desirable to provide a cloth 35 to cover the wrappers further to protect the same from the atmosphere, and at the same time, not to interfere with the operator's ready access thereto, I provide such a cloth 54 secured at the front edge by a rod 55 engaging the hooks 56 connected with the lid 21. The rear edge of the cloth is provided with another rod adapted to lie upon the platen 14 to the rear of the pile of wrappers. When the lid is closed the cloth 45 covers the top of the pile of wrappers as shown in Fig. 9, and when the lid is open the front portion of the cloth is lifted free from the wrappers to give the operator access thereto.

50 The operation of the device is as follows:—By pressure on the toe end 36 of pedal member 32 the connecting rod 38 is pulled down causing the elevation of the front end of lever 41; which movement is 55 communicated through the connecting rods 43 and 44 to the lid 21 causing the same to be elevated or moved to the open position, as indicated in dotted lines in Fig. 5. Upon relieving the pressure on the toe end of 60 pedal 32, when the lid has sufficient weight, as in the present instance, it will close by gravity, or it may be closed positively by pressure on the heel portion of the pedal.

It is to be noted that the pivots 49, 50 65 and 51 have axes parallel with each other,

while the axes of pivots 52 and 29 are parallel with each other, but are arranged at an angle with the axes of the first three pivots mentioned.

The locking member 20 which is pivotally secured to the lug 19 on the bottom of box 12 is adapted to engage with either one of slots 46 and 47, depending upon the position of the lid, that is whether in the open or closed position, and thus to lock the lid 75 in such position.

The purpose of providing the oppositely extending ears 33 on the pedal member 32 is for securing means for reversing the said pedal so that the extension 37 may be directed to the left hand of the operator or to the right hand of the operator as desired, so as to provide means for operating the box lid, with the box located on the left hand side of the table, or on the right hand 85 side of the table, so as to accommodate either the left handed or right handed operator.

It will be understood that in shifting the mechanism from the right hand position as 90 shown in the drawings to a left hand position, it is only necessary to change the position of the lug or hanger 42, or else to connect the lever 41 with another similar lug or hanger 42 provided on the left hand side 95 of the table, and to connect the connecting rod 45 with a pin extending from the opposite end of the lid from that shown in Fig. 3. It will also be understood that the pedal member 32 is slidable on the rod 29 to the 100 desired position.

What I claim is:—

1. A humidor for a cigar maker's table comprising a cast-metal receptacle and a pressed metal lid movably connected therewith having its marginal extensions in a horizontal plane when the lid is brought to rest on the top of the receptacle and the intermediate body of the lid depressed below the level of the surrounding margin 110 and lying in a plane inclined to the plane of said margin.

2. A humidor for a cigar maker's table comprising a receptacle having its bottom inclined to the horizontal, a drain cock at 115 the lower portion of said inclined bottom and a perforated platen having supporting legs resting on the inclined bottom so proportioned as to maintain the platen horizontal.

3. A humidor for a cigar maker's table comprising a cast-metal receptacle and a lid movably connected thereto, a lid actuating mechanism and a locking device for engaging said actuating mechanism to lock the lid 125 in either the open or closed position.

4. A humidor for a cigar maker's table comprising a receptacle, a lid movably connected therewith provided on one side with hinge elements, inclining from the hinged 130

side downwardly into the box when in the closed position, and provided on the other three sides with upwardly and then horizontally extending flanges, said upwardly extending flanges adapted to fit within the receptacle and the horizontally extending flanges adapted to fit over the edge of the receptacle.

5. A humidor comprising a receptacle, a lid movably connected therewith having upwardly extending flanges, metal pieces secured to the lid within the flanges and flush with the top portion thereof and a lever supporting pin connected with one of said metal pieces.

6. A humidor comprising a receptacle, a lid movably connected therewith having upwardly extending flanges, metal pieces secured to the lid within the flanges and flush with the top portion thereof, and a pin extending from one of said pieces and through the upwardly extending side flange adjacent thereto.

7. A humidor comprising a long narrow receptacle and a lid provided with a marginal flange lying in a horizontal plane when the lid engages the top of the receptacle, said lid hinged to one of the long upper margins thereof, the surface of the lid within the marginal flanges depressed below said horizontal plane and inclined downwardly toward the opposite long edge of the receptacle and then extending upwardly to the adjacent horizontal flange, the upper margin of the receptacle adjacent thereto being provided with a yielding and moisture proof strip to engage the horizontal flange close to said upwardly extending portion.

8. A humidor comprising a long narrow receptacle and a lid provided with a marginal flange lying in a horizontal plane when the lid engages the top of the receptacle, said lid hinged to one of the long upper margins thereof, the surface of the lid within the marginal flange depressed below said horizontal plane and inclined downwardly toward the opposite long edge of the receptacle and then extending upwardly to the adjacent horizontal flange, the upper wall of the receptacle adjacent thereto of relatively increased thickness and channeled and a resilient moisture proof strip secured in said channel for engaging the horizontal flange of the lid close to the juncture of the said flange and said upwardly extending portion.

9. A cigar maker's humidor comprising a receptacle, a lid movably connected therewith, and a covering cloth adapted to be automatically lifted when the lid is lifted.

10. A cigar maker's humidor comprising a receptacle, a lid movably connected therewith, a covering cloth for the tobacco within the receptacle, and means whereby the

front edge of the cloth is lifted when the lid is moved to the open position.

11. A humidor for a cigar maker's table, comprising a receptacle and means for securing the same to the table, a lid movably connected therewith, a pedal having an angular extension to one side thereof, a lever pivotally connected with the table, connecting means between pedal and lever and between lever and lid for establishing operative relationship therebetween.

12. A humidor for a cigar maker's table comprising a receptacle for the cigar wrappers and means for maintaining the same moist, a pedal having an angularly disposed extension and oppositely disposed journal bearings on the pedal and means on which either of the bearings may be supported, for the purpose of reversing the direction of the angularly disposed extension and connecting mechanism between said extension and the lid adapted to serve as means for operating the lid either for a left hand or a right hand table.

13. A humidor for a cigar maker's table comprising a receptacle, means for securing the same to the table to one side thereof, a lid movably connected with the receptacle and actuating means therefor comprising a pedal, a rod pivotally connected with the pedal, a rod pivotally connected with the lid, and an intermediate rocking lever mounted on a stationary support and connected at its opposite ends with said rods, said rocking lever normally extending in a substantially horizontal plane at an angle with the axis of the lid.

14. In combination with a cigar maker's table, a humidor for cigar wrappers, comprising a receptacle, means therein for maintaining the wrappers moist, a lid movably connected therewith, a pedal and pedal supporting means, a pivotally mounted actuating lever, a connecting rod between the pedal and actuating lever and two rods pivotally connected together, one of said rods pivotally connected at one end to the actuating lever and the other rod pivotally connected at one end to the lid.

15. A humidor for a cigar maker's table comprising a receptacle for cigar wrappers, means therein for maintaining the wrappers moist, a lid movably connected therewith, a pedal and pedal supporting means, a pivotally mounted lid actuating lever, a connecting rod connected between the pedal and lever, two pivotally connected rods, one of said rods pivotally connected at one end with the lever and the other rod pivotally connected at one end with the lid, the axes of the pivots connecting one rod with the lid and with the other rod being parallel and at right angles to the axis of the pedal movement.

16. A humidor for a cigar maker's table,

4
a lid movably connected therewith, a pedal, a pivotally mounted lever, a connecting rod between pedal and lever, a jointed connecting rod pivotally connected between the lever and the lid, the axes of the joint and the lid pivots being parallel and at an angle with the axis of movement of the lever.

17. A humidor for a cigar maker's table comprising a receptacle, a lid movably connected therewith, a pedal and connecting mechanism for establishing operative relationship between pedal and lid and a locking member for arbitrarily locking the actu-

ating means with the lid either in the open or closed position.

18. A humidor for a cigar maker's table comprising a receptacle, a lid movably connected therewith, actuating means for the lid comprising a pedal, a pivoted lever and connecting mechanism including an extensible connecting rod and means for securing the adjustment of such extension.
